POUNCING MACHINE

Paul Schultze, Danbury, Conn., assignor to Doran
Brothers, Incorporated, Danbury, Conn.

Application August 24, 1938, Serial No. 226,442

44 Claims. (Cl. 223—20)

This invention relates to a machine for pouncing or finishing hat bodies.

One of the objects of this invention is to provide a machine for finishing hat bodies which is simple in construction, efficient in operation, and sturdy and durable under conditions of rigorous use. Another object is to provide a machine of the above nature which is largely automatic in operation and does not necessitate the attention of skilled labor. Another object is to provide a machine of the above nature capable of imparting a smooth velvety finish to a hat without the production of any tool marks thereon. Other objects will be in part apparent and in part pointed out hereafter.

The invention accordingly consists in the features of construction, combinations of elements and arrangements of parts as will be exemplified in the structure to be hereinafter described and the scope of the application of which will be indicated in the following claims.

In the accompanying drawings in which are shown several embodiments of my invention,

Figure 1 is an elevation of one side of my machine;

Figure 2 is a fragmentary sectional elevation of the tool operating mechanism;

Figure 3 is a sectional elevation taken along the line 3—3 in Figure 2;

Figure 4 is an enlarged top plan view of the tool assembly mounting;

Figure 5 is a sectional elevation taken along the line 5—5 in Figure 4;

Figure 6 is a fragmentary side elevation of a modified form of my machine;

Figure 7 is an enlarged fragmentary elevation partly in section of the tool shown in Figure 6 operating on a hat mounted on the hat block; and,

Figure 8 is an enlarged fragmentary sectional elevation of the hat block supporting and operating head of the machine shown in Figure 6. This view also is illustrative of a modification of the machine shown in Figure 6.

Similar reference characters refer to similar parts throughout the various views of the drawings.

In general, and with reference to Figure 1, my pouncing machine comprises a column generally indicated at 10, formed by a base 11, a motor housing 12, an extension 13 and a head 14. Preferably these parts are separate castings which may be secured together in any suitable manner.

A shaft 15 is journaled in head 14 and has secured on one end thereof a chuck 16 which

carries a hat block 17 on which a hat body 18 may be mounted. On the other end of shaft 15 is a driven pulley 19 connected by a belt 20 to a driving pulley 21, associated with a clutch generally indicated at 22. Clutch 22 is driven by a motor 23 mounted in housing 12 and thus shaft 15 may be driven to rotate hat block 17. Motor 23 also drives an oil pump 24 by means of pulleys 25 and 26 connected by a belt 27. Preferably pump 24 is mounted in the upper part of base 11 of column 10.

A pouncing tool assembly generally indicated at 28 is rotatably mounted on a bracket generally indicated at 29 and extending from base 11, this assembly being movable about and toward and away from hat block 17 through instrumentalities to be described hereinafter. Pouncing tool assembly 28 includes a pouncing tool generally indicated at 30 and driving mechanism therefor as will be described in detail hereinafter.

Oil pump 24 supplies oil under pressure to hydraulic mechanism disposed in and on base 11, and partially housed within a casing 31. For a detailed description of this hydraulic mechanism and its operation, reference is made to my United States Patent No. 2,137,250.

The hydraulic mechanism includes a piston (not shown) connected to a rack the end of which is shown at 32 (Figure 1) and this rack meshes with a gear or train of gears (not shown) as desirable to rotate a heavy stud 33 to which a bracket 34 is secured.

Tool assembly 28 is connected to bracket 34 and accordingly upon operation of the hydraulic mechanism which effects rotation of hollow stud 33 (see also Figure 5) pouncing tool assembly 28 is moved about hat block 17 in a substantially circular path. The above-described driving connections between the hydraulic mechanism and tool assembly 28 is also particularly described in my above-noted copending application.

Referring now to Figure 5, bracket 34 is rotatably mounted on bracket 29 by an anti-friction bearing 35, and the free end of bracket 34 has secured thereto a pair of springs 36 which have connected thereto a tool assembly supporting bracket 37. Bracket 37 has secured therein a stud 38 on the ends of which is rotatably mounted a supporting plate 39. Stud 38 also carries a casing 40 which houses a spring (not shown) the tension of which is adjustable by knob 41. This spring is suitably connected to tool assembly 28 (Figure 1) and its tension is adjustable by knob 41 to bias tool assembly 28 toward hat block 17.

at various desired pressures, all as is described in detail in my above-noted Patent No. 2,137,250.

Referring back to Figure 5, supporting bracket 39 includes a generally ovate slot 42 (see also Figure 4) which adjustably receives the tubular portion 43 of a support generally indicated at 44. Support 44 includes an integral plate 45 provided with slots 46 (see also Figure 4) which receive machine bolts 47 adapted to be threaded into supporting plate 39 to secure support 44 thereto. Support 44 also includes upper and lower shoulders 48 and 49 (Figure 5) respectively, in which anti-friction bearings 50 and 51 are set. These bearings rotatably carry the tubular extension 52 of a plate 53, extension 52 being disposed within tubular portion 43 of support 44 and held therein by a collar 54. Plate 53 also has a pair of slots one of which is shown at 55 through which machine bolts 56 are adapted to extend for a purpose to be described hereinafter.

With reference to Figure 1, tool assembly 28 comprises a motor housing 57, a crank case 58, a casing 59 and a housing 60. Preferably these various portions of tool assembly 28 are separately cast or fabricated and are bolted or screwed together in any desirable fashion. If desired, housing 60 may be connected to casing 59 by a driven fit. Motor housing 57 includes a base 61 which, with reference to Figure 5, rests on the machined top of plate 53. Bolts 56 are threaded into motor housing base 61, and as these bolts extend through slots 55, the motor base is adjustable along plate 53. Thus tool assembly 28 is adjustably connected to plate 53 which, through its variable connection with support 44, is adjustable or movable with respect to supporting plate 39, i. e. the tool assembly as a unit is pivotable about the axis of extension 52 of plate 53. Hence, what will hereinafter be termed the swivel axis of the tool is adjustable toward and away from what will hereinafter be termed the swinging axis of the tool (the axis of stud 38) by virtue of the adjustable connection afforded by bolts 47 which extend through slots 46 into supporting plate 39. The purpose of the adjustments afforded by support 44 and plate 53 will be described below.

With reference to Figure 1, motor housing 57 is adapted to receive a motor 62 which is adjustably held within the housing by a strap (not shown) which may be taken up by a nut 63 to hold the motor in its set position. Motor 62 is connected by means of pulleys 64 and 65 and belt 66 to the mechanism in crank case 58.

As is more clearly shown in Figure 2, crank case 58 has suitably set therein a pair of anti-friction bearings 67 and 68 which rotatably carry a shaft 69, the outer end of which is borne by an anti-friction bearing 70 set in an extension 71 bolted to the side of crank case 58, and it is on this shaft 69 that the driven pulley is mounted. Shaft 69, which in fact is the crank shaft, includes throws or eccentrics 72, 73 and 74, about which are respectively mounted anti-friction bearings 75, 76 and 77. Bearing 76 carries a connecting rod 78 to which is bolted an operating rod 79 or the like, this rod preferably being formed of an extremely light but strong alloy, such as "Dow" metal. The upper portion 79a of rod 79 is preferably sprayed with steel or a suitable alloy thereof and ground to provide a bearing surface capable of reciprocating in a bushed guide 80, whose upper integral end 81 has extending trunnions 82 and 83 journaled in suitable bushings 84 and 85 mounted in housing 75

60. The upper end of housing 60 has an annular shoulder 86 to carry a flanged cap 87 whose sides 88 extend downwardly about and around housing 60 and the ends of trunnions 82 and 83. It will now be clear that upon rotation of crank shaft 69, connecting rod 78 and accordingly operating rods 79 are reciprocated along the axis of the rods and rocked about the axis of trunnions 82 and 83.

As shown in Figure 1, pouncing tool 30 is connected in any suitable manner to the top of rod 79 and accordingly partakes of the movement of the rod; thus the tool travels in a substantially elliptical path. It should also be noted as pointed out above, that the tool is capable of traversing hat 18 in a path extending from the crown to the brim, i. e. in a path substantially conforming to the contour of hat block 17. Furthermore, the tool is movable toward and away from the head about its swinging axis through the coaction of a cam 200 and roller 201 as described in detail in my above-noted copending application. It should also be noted that tool 30 is freely movable with relation to the head about its swivel axis described above.

While mechanism has heretofore been provided for driving a pouncing tool through an elliptical path as for example the mechanism disclosed by Cassé in his United States Patent No. 2,006,260, there are many advantages to be derived from completely dampening vibration resulting from the pure rectilinear reciprocation of the tool and for counteracting the rocking forces resulting from movement of the tool through its elliptical path while at the same time providing a freely swiveling tool which is not positively constrained to any definite position with respect to its swivel axis. To this end I have provided a pair of sliding shoes 89 and 90 whose lower ends encircle and accordingly are carried and driven through anti-friction bearings 75 and 77 by crank shaft 69. As these shoes are substantially the same, only one will be described in detail. Thus shoe 89 (Figure 3) is cored out to provide a runway 91 which embraces the sides of a rocking guide 92 having formed thereon a hollow boss 93 (Figure 2). This boss is mounted on a stud 94 the outer disc-like end 95 of which is disposed between the outer end of boss 93 and the inside surface of a plate 96, which is bolted to housing 59 by bolts 97. Similarly sliding shoe 90 is provided with a rocking guide 98 pivoted on a stud 99 held in place in housing 59 by a plate 100 bolted thereto. Preferably the lower ends of rockers 92 and 98 are cored out while the upper ends thereof are solid. The upper ends of the two sliding shoes 89 and 90 are tied together by straps 101 and 102 (Figure 3) bolted thereto by bolts 103, and together weigh exactly the same as connecting rod 78, operating rod 79 and tool 30 (Figure 1). Thus the sliding shoes dampen substantially all vibration resulting from reciprocation of the rods and tool. Also, the weight of rockers 92 and 98 is so related to the weight of rod 79 and tool 30 that vibration resulting from rocking forces of the rod and tool is forcibly damped out, i. e., rockers 92 and 98 rock oppositely to rod 79 and tool 30. By reason of the opposite disposition of crank shaft throws 72 and 73 with respect to throw 74, sliding shoes 89 and 90 reciprocate oppositely to the reciprocation of connecting rod 78 and rod 79.

It will now appear that in view of the above-described counter-balancing features, and in view of the resilient mounting of tool assembly 28 on

bracket 34 by springs 36 (Figure 5) substantially all vibration resulting from operation of the tool and its driving mechanism are absorbed and are not transmitted to the main column 10 of the pouncing machine. The advantages of this, it is believed, are apparent, but it might be well to note that the complete absence of vibration in the column of the machine prevents any vibration of the hat block and thus precludes all relative motion between the hat and the tool except that desired.

As hereinbefore noted, tool assembly 28 (Figure 1) and accordingly tool 30 is freely pivotable about the tool's swivel axis, i. e., the axis of plate extension 52 (Figure 5). Under certain circumstances, it might be desirable to move this swivel axis toward or away from the hat block, and this may readily be accomplished by loosening bolts 47 and moving support 44 relative to supporting plate 39. This variation in the swivel axis however, would move the pouncing tool too far from or too close to the hat. Accordingly a compensating adjustment is made by unloosening bolts 56 and thence moving motor housing base 61 over plate 53 by an amount equal to the adjustment between support 42 and supporting plate 39. If after this adjustment it is found that the tool assembly has become unbalanced (it being desirable that assembly 28 be in substantially perfect balance in order that the tool may freely pivot about its swivel axis) motor 62 (Figure 1) may be moved to the right or left in its housing 57 to bring the assembly back into balance.

While the above-described adjustment may not often be necessary, it occasionally is so by reason of a hat block of different contour or depth being used. Thus for a hat block wherein the square is quite sharp and pronounced, one adjustment may be necessary which is quite different from the swivel point setting desirable for a hat block with a rounded square.

Furthermore, in connection with hat blocks of varying depth, I have provided (as shown in Figure 4) a bent plate 104, one end of which is bolted to motor housing 61 and the other of which is adapted to enter a notch 105 formed in an eccentric 106 mounted on a rotatable shaft 107 carrying an operating knob 108 at one end, and an indicating disc 109 at the other. Preferably disc 109 is graduated according to different hat block depths and registers with a suitable indicator so that the operator of the machine may immediately set the disc at the desired indication. Turning of knob 108 accordingly rotates eccentric 106 and raises or lowers bent plate 104 to adjust tool assembly 28 about its swinging axis, i. e. axis of stud 38, so that the tool is correctly presented to the tip of the hat on the block. Engagement of plate 104 in notch 105 serves a further purpose in preventing the motor housing 61, the crank case and pouncing tool assembly from swiveling while the whole unit is lifted out of engagement with the hat body.

The pressure with which the tool is forced against the hat is controlled in substantially the same manner as that described in my above-referred to patent No. 2,137,250. Thus, referring to Figure 4, a leaf spring 110, the tension of which may be adjusted, biases the tool assembly 28 (Figure 1) away from hat block 17 while the spring in housing 40 urges the tool assembly toward the hat block. Hence, by adjusting the tension in both springs, proper pressure of the tool against the hat may readily be obtained.

The machine as shown in Figure 1 is operated

through the system of levers A (Figure 1) as described in my above-noted Patent No. 2,137,250. By virtue of the balanced free swiveling elliptically moving pouncing tool 30, a hat of any contour, i. e. a hat having a sharp or rounded square, may be given a soft, velvet-like finish free from any tool marks. Pouncing tool 30 also includes mechanism for automatically feeding abrasive paper over the pad substantially as described in detail in my above-referred to copending application.

While the above-described machine is particularly well adapted to pouncing blocked hats, it is necessary to pounce unblocked hats, particularly hat bodies being prepared for the manufacture of women's hats. Such hat bodies often have no definite head size, and often are quite deep and generally conical in shape. Hat bodies of this nature accordingly preclude the mounting thereof on hat blocks such as hat block 17 in Figure 1, i. e. hat blocks turned to a definite head size for conformation. Therefore, to obviate the difficulties encountered in hand pouncing such hat bodies, the pouncing machine shown in Figure 6 is directed. In general organization, this machine is similar to that shown in Figure 1, and accordingly includes column 10 comprising base 11, a motor housing 12 and extension 13. However, a special head generally indicated at 111 is mounted on extension 13 and this head rotatably mounts a spindle 112 driven by motor 23 through pulleys 113, 114 and belt 115. As is more clearly shown in Figure 8, spindle 112 is rotatably mounted in a journal 117 and is slidably mounted for rotation and also axial movement within a journal 11a, the spindle having associated therewith clutch mechanism generally indicated at 118 which is operated by engaging and disengaging apparatus generally indicated at 119. For a detailed description of the details of construction and operation of the spindle clutch and its operating mechanism, reference is made to my U. S. Patent No. 2,105,130.

The left-hand end of spindle 112, as viewed in Figure 8, has secured thereto a back support generally indicated at 120 having a tubular hub portion 121, which carries anti-friction bearings 122 and 123 in which a reduced end 112a of spindle 112 is rotatably mounted. The lower end of back support 120 has a boss 124 in which is secured an end 125a of a rod 125, to the other end of which a piston 126 is attached. Piston 126 is adapted to reciprocate in a cylinder 127 secured to head 111, as oil under pressure is fed into one end or the other of the cylinder, as particularly described in my above-noted U. S. Patent No. 2,105,130. When piston 126 is actuated, as noted in my patent, spindle 112, and accordingly support 120, are moved axially and this for a purpose to be described.

The extreme end 112b of spindle 112 is further reduced and has secured thereto so as to rotate therewith a spider 128. The right-hand end of spider 128, as viewed in Figure 8, is formed in an annulus or ring 129 and has secured thereto a block 130 as by screws 131, block 130 having a generally frusto-conical shape. The outer surface of the block is covered preferably with a piece of felt 132 or the like. Back support 120 at its larger end 120a is annular and has attached thereto a hood 133 by bolts 134.

As is more clearly shown in Figure 6, hood 133 has an enlarged slot 135 formed therein and extending from near the base of the hood over the tip or rounded end of the hood, so as to ex-

pose a substantial portion of felt covered block 130. Hood 133 is so mounted that slot 135 is arranged in registry with pouncing tool 30 so that when the tool traverses a hat body mounted on the hood, it travels in a path extending from the tip of the hat toward the brim thereof. As noted above, however, the hat body is often of substantial depth, and accordingly extends farther over hood 133 than the limit of traverse of the tool therealong. It is for this reason that axial movement of hat block spindle 112 and the parts attached thereto are axially movable. Thus, as described in my U. S. Patent No. 2,105, 130, after the tool has reached the extent of its travel, the spindle, and accordingly hood 133 is automatically actuated to move the hat body past the tool as the tool continues to operate until all portions of the hat have been pounced, and thereafter reverse the movement of the hat back to the point where reversal of the movement of the tool is automatically begun.

In view of the fact that hat bodies pounced on the machine just described vary substantially in head size, I have provided means for holding the hat in a position where the tool can operate on it and also for feeding the hat past the elliptically moving tool. This holding and feeding mechanism, as shown in Figures 6 and 7, comprises a system of piping 136 connected to a suitable source of compressed air, and connected at its upper end to a header 137 from which a pair of pipes 138 and 139 lead respectively to T's 140 and 141. Each of these T's has connected thereto a pair of pipes 142 and 143 which terminate in nozzles or jets 144 and 145, respectively, at the bottom and top edges of pouncing pad 30a and adjacent the operative surface thereof. As is best shown in Figure 7 nozzles 144 and 145 are so directed that blasts of air issuing therefrom impinge against a hat 146 mounted on hood 133 at points respectively adjacent the lower and upper edges of hood slot 135. The air issuing from jets 134 and 135 is of sufficient pressure to blow hat 146 firmly enough against felt covered block 130 so that the hat adheres thereto as the block rotates. Thus hat 146 is rotated, for example, in the direction of the arrow, and as its lower portion 146a moves over the bottom edge of slot 135, the air pressure from nozzles 144 forces it against felt covered block 130. Similarly, as upper portion 146b of the hat moves against the upper edge of slot 135, the hat is peeled from the hat block so as to ride over the outer surface of hood 133. Hence, it may be seen that that part of the hat between portions 146a and 146b thereof is held against the rotating hat block in a position where it may be worked on by pouncing tool 30.

If for any reason the hat body 146 is not of sufficient depth to completely cover slot 135 shown in Figure 6, a suitable shutter or the like (not shown) may be provided for hood 133 to cover that portion of slot 135 not covered by the hat body. Air pipes 136 may be connected in any suitable manner to tool assembly 28 and have 60 any type of suitable connections such as ball and socket joints or flexible tubing, which will not interfere with the free swiveling of the tool assembly. Furthermore, by the provision of the symmetrically placed nozzles 144 and 145, i. e. 70 symmetrical with respect to pouncing pad 30a, the air pressure against the hat on each side of the pouncing pad is substantially equal and accordingly tends to keep the pad in proper tangential position with respect to the hat block 75

without, however, adversely affecting free swiveling of the pouncing tool.

Under certain circumstances, it may be desirable to hold the hat body against hood 133 by negative pressure instead of positive pressure. In view of the fact that the only opening in hood 133 is that provided by slot 135, a partial vacuum can be maintained within the hood when a hat body is placed thereover so as to cover the slot. This partial vacuum has the same effect in holding a hat body against block 130 as does the positive pressure exerted by the jets directed against the outer surface of the hat body. Hence, with reference to Figure 8, I have provided a pipe fitting 147 registering with an opening 148 in back support 120. Any suitable piping (not shown) may be connected to fitting 147 and with any suitable evacuating system. If desired, a pump (not shown) may be disposed within column 20 extension 13 or elsewhere in or on the machine and pneumatically connected with fitting 147 and accordingly with the inside of hood 133. It follows, that upon operation of such a pump, air is sucked from within the hood, and a hat disposed thereon is pulled against block 130 so as to rotate therewith as hereinbefore described.

Accordingly I have provided a pouncing machine which accomplishes the various objects hereinbefore set forth in a thoroughly practical and efficient manner.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a machine of the character described, in combination, a base, a hat support on said base adapted to support a hat, means for rotating said hat support, a tool for operating on said hat, a support for said tool including mechanism for driving it through a closed substantially elliptical path, means for effecting relative movement between said supports and means for freely pivotally supporting said tool support in operative relation to said hat support for unrestrained swiveling movement in relation thereto.
2. In a machine of the character described, in combination, a base, a hat support on said base adapted to support a hat, a tool for operating on said hat, a support for said tool including mechanism for driving the tool through a closed substantially elliptical path, means for effecting relative movement between said supports, a bracket attached to said base and extending from the lower portion thereof beneath said hat support, and anti-friction means on said bracket for freely pivotally supporting said tool support in operative relation to said hat support so that the tool support is unrestrainedly swivelable in relation to the hat support.
3. In a machine of the character described, in combination, a base, a hat support on said base adapted to support a hat, a tool for operating on said hat, a support for said tool including mechanism for driving it through a closed substantially elliptical path, means for effecting relative movement between said supports, means for freely pivotally supporting said tool support in operative relation to said hat support for unrestrained swiveling movement in relation thereto, and means for changing the position of said tool support in relation to said hat support so

that the swivel axis of the tool support may be displaced in relation to the hat support.

4. In a machine of the character described, in combination, a base, a hat support on said base adapted to support a hat, a tool for operating on said hat, a swingable support for said tool including mechanism for driving it, means for freely pivotally supporting said tool support in operative relation to said hat support for unrestrained swiveling movement in relation thereto, and means for displacing said tool support relative to said hat support so that the swivel axis of the tool support may be varied in relation to the hat support.

5. In a machine of the character described, in combination, a base, a hat support on said base adapted to support a hat, a tool for operating on said hat, a swivelable support for said tool including mechanism for driving the tool, and means including a pair of parts attached respectively to said base and to said tool support, said parts and said base being relatively movable to vary at will the position of the swivel axis of the tool support in relation to the hat support without changing the position of the tool with respect to the hat.

6. In a machine of the character described, in combination, a base, a hat support on said base adapted to support a hat, a tool for operating on said hat, a swingable support for said tool including mechanism for driving the tool through a closed substantially elliptical path, means for freely pivotally supporting said tool support in operative relation to said hat support for unrestrained swiveling movement in relation thereto, a motor for operating said tool driving mechanism secured to said tool support, and means for varying at will the position of said motor transversely of the axis of said tool support to change the center of mass thereof.

7. In a machine of the character described, in combination, a base, a hat support on said base adapted to support a hat, a tool for operating on said hat, a support for said tool including mechanism for driving the tool, means for pivotally supporting said tool support in operative relation to said hat support for free swiveling movement in relation thereto, means for moving said tool support toward and away from said hat support to vary at will the position of the swivel axis of the tool support in relation to the hat support, a motor carried by said tool support for operating said tool driving mechanism, and means for varying at will the position of said motor transversely of the swivel axis of the tool support to vary the center of mass of the tool support.

8. In a machine of the character described, in combination, a base, a hat support on said base adapted to support a hat, tool means connected to said base and support in operative relation to said hat support, said tool means including a tool, driving mechanism therefor and a motor for operating the driving mechanism, said motor being disposed below said driving mechanism, and means for varying the position of said motor transversely of said driving mechanism while the machine is inoperative, whereby the center of mass of the tool means may be varied at will.

9. In a machine of the character described, in combination, a base, a hat support on said base adapted to support a hat, tool means for operating on said hat, a bracket pivotally connected to said base, a support associated with said bracket and movable toward and away from

the pivotal axis thereof, a second support pivotally swivelably mounted in said first support so as to be freely swivelable in relation thereto, and means for movably securing said tool means to said second support whereby said tool means may be moved relative to the swivel axis of said second support.

10. In a machine of the character described, in combination, a base, a hat support on said base adapted to support a hat, tool means for operating on said hat, a plurality of parts for mounting said tool means in operative relation to said hat support, at least two of said parts being relatively swivelable, said parts also being individually movable transversely of the swivel axis, whereby the position of the swivel axis may be varied at will with respect to the hat support.

11. In a machine of the character described, in combination, a base, a hat support on said base adapted to support a hat, a tool assembly comprising a motor housing, a crank case supported on said motor housing and a tool driven by mechanism in the crank case, said tool driving mechanism being adapted to drive the tool in an elliptical path, means mounting said tool assembly for free swivel movement with relation to said hat support, and means for varying at will the position of the swivel axis of the tool assembly with relation to the hat support.

12. In a machine of the character described, in combination, a base, a hat support operatively associated with said base, a tool support operatively associated with said base, means for effecting relative movement between said supports, a tool mounted for elliptical movement on said tool support, means for moving said tool, means for dampening vibration resulting from the rectilinear reciprocable component of the elliptical movement, and means for dampening vibration resulting from the rocking forces generated by said elliptical motion.

13. A tool assembly for a machine of the character described comprising, in combination, a housing, a crank shaft rotatably mounted in said housing and having at least two throws thereon, a tool rod connected to one of said throws and extending from said housing, a tool on said tool rod, a balance rod connected to another of said throws and disposed in said housing, and a rocker operatively associated with said balance rod to coat therewith in dampening vibration resulting from operation of said tool rod and tool.

14. A tool assembly for a machine of the character described comprising, in combination, a housing, a crank shaft rotatably mounted in said housing and having a plurality of throws mounted thereon, a tool rod connected to one of said throws and extending from said housing, a tool mounted on said tool rod and movable through an elliptical path upon operation of said crank shaft, a balance rod mounted on another of said throws and extending therefrom within said casing, said balance rod having a guideway formed therein, and a rocker disposed within said housing and pivotally connected thereto, said rocker being slidably related to said guideway and adapted to coat with said balance rod to dampen all vibration resulting from operation of said tool.

15. A tool assembly for a machine of the character described comprising, in combination, a housing, a crank shaft rotatably mounted in said housing having a plurality of throws formed thereon, a tool rod connected to one of said throws

for operation thereby, a tool on said tool rod, a balance rod connected to another of said throws and extending within said housing on one side of said tool rod, a second balance rod connected to another of said throws and extending within said housing on the other side of said tool rod, and rocker means associated with said balance rods and adapted to coact therewith in dampening vibration resulting from operation of the rod and tool.

16. A tool assembly for a machine of the character described comprising, in combination, a housing, a crank shaft rotatably mounted in said housing having a plurality of throws formed thereon, a tool rod connected to one of said throws for operation thereby, a tool on said tool rod, a balance rod connected to another of said throws and extending within said housing on one side of said tool rod, a second balance rod connected to another of said throws and extending within said housing on the other side of said tool rod, and rocker means associated with said balance rods and adapted to coact therewith in dampening vibration resulting from operation of the rod and tool, said rocker means including a pair of rockers pivotally mounted within said casing and slidably associated with said balance rods.

17. A hat support for a machine of the character described comprising, in combination, a rotatable spindle, a hat block secured to said spindle and rotatable therewith, a stationary hood substantially concentric with said hat block and disposed thereover, said hood having an elongated slot formed therein extending generally from the tip portion of the hat block toward the brim portion thereof, said hood being adapted to support a hat, and pneumatic means for forcing that portion of a hat mounted on said hood which overlies said slot against said hat block.

18. A hat support for a machine of the character described comprising, in combination, a rotatable spindle, a hat block secured to said spindle and rotatable therewith, a stationary hood substantially concentric with said hat block and disposed thereover, said hood having an elongated slot formed therein extending generally from the tip portion of the hat block toward the brim portion thereof, said hood being adapted to support a hat, and pneumatic means for forcing that portion of a hat mounted on said hood which overlies said slot against said hat block, said pneumatic means including at least one air jet adapted to direct a stream of compressed air against a hat in the vicinity of said slot.

19. A hat support for a machine of the character described comprising, in combination, a rotatable spindle, a hat block secured to said spindle and rotatable therewith, a stationary hood substantially concentric with said hat block and disposed thereover, said hood having an elongated slot formed therein extending generally from the tip portion of the hat block toward the brim portion thereof, said hood being adapted to support a hat, and pneumatic means for forcing that portion of a hat mounted on said hood which overlies said slot against said hat block, said pneumatic means including mechanism for evacuating the interior of said hood to draw the hat through said slot against said block.

20. In a machine of the character described, in combination, a rotatable hat support adapted to support a hat, a freely swivelable tool for operating on the surface of said hat, and pressure means

for maintaining said tool in proper operative position with respect to said hat, said pressure means including a plurality of air jets adjacent said tool adapted to blow streams of air against the hat.

21. In a machine of the character described, in combination, a rotatable hat support adapted to support an unblocked hat, a tool for operating on the surface of the hat, means for effecting relative movement between the tool and hat support in a path extending from the tip of the hat toward the brim portion thereof, pneumatic means for holding the hat in operative position on the hat support as it is operated on by said tool, and means for moving the hat support axially past the tool.

22. In a machine of the character described, in combination, a base, a hat support associated with said base, the periphery of said hat support being formed to receive a hat thereon, tool means for operating on a hat mounted on said hat support, means for driving said tool, means for effecting relative movement between said tool means and said hat support, and pneumatic means for holding the hat on said hat support in proper operative position.

23. In a machine of the character described, in combination, a base, a hat support associated with said base, the periphery of said hat support being formed to receive a hat thereon, tool means for operating on a hat mounted on said hat support, means for driving said tool, means for effecting relative movement between said tool means and said hat support, and means including an air jet directed toward the hat support for holding the hat thereon in proper operative position.

24. In a machine of the character described, in combination, a base, a hat support associated with said base, the periphery of said hat support being formed to receive a hat thereon, tool means for operating on a hat mounted on said hat support, means for driving said tool, means for effecting relative movement between said tool means and said hat support, and means associated with said hat support for effecting a vacuum in the vicinity thereof to maintain a hat mounted thereon in proper operative position.

25. In a machine of the character described, in combination, a base, a hat support associated with said base, tool means for operating on a hat mounted on said hat support, means for effecting relative movement between said tool means and said base, and a plurality of air jets adapted to direct streams of air against the outer surface of a hat mounted on said hat support to supplement the action of the tool thereon.

26. A hat support for a machine of the character described comprising, in combination, a rotatable spindle, a hat block secured to said spindle and rotatable therewith, a stationary member associated with said hat block and positioned with respect thereto that a hat mounted on said stationary element may be engaged by said hat block, and means for forcing a portion of the hat against said hat block whereby rotation of the block moves the hat relative to said stationary member.

27. A hat support for a machine of the character described comprising, in combination, a rotatable spindle, a hat block secured to said spindle and rotatable therewith, a stationary member associated with said hat block and positioned with respect thereto that a hat mounted on said stationary element may be engaged by said hat

block, and means for evacuating said stationary element whereby a hat mounted thereabout is drawn against said hat block so that rotation of the block moves the hat relative to said stationary member.

28. In a machine of the character described, in combination, a rotatable hat support adapted to support a hat, a tool for operating on the surface of said hat, and a plurality of air jets symmetrically arranged with respect to said tool and adapted to direct streams of air against a hat mounted on said hat support to maintain said tool in proper operative position with respect thereto.

29. In a machine of the character described, in combination, a rotatable hat support adapted to support a hat, a tool for operating on the surface of said hat, and pneumatic means mounted with said tool for maintaining said tool in proper operative position with respect to said hat.

30. In a machine of the character described, in combination, a rotatable hat support adapted to support a hat, a freely swivelable tool for operating on the surface of said hat, and pneumatic pressure means associated with said tool for maintaining said tool in proper operative position with respect to said hat.

31. In a machine of the character described, in combination, a hat support and a base therefor, a bracket pivotally connected to said base, a supporting plate pivotally secured to said bracket, a tubular element adjustably secured to said supporting plate and movable relative to the pivotal axis of said bracket, a support rotatably mounted in said plate, and a tool assembly adjustably secured to said support and movable transversely of the axis thereof.

32. In a machine of the character described, in combination, a base, a hat support on said base adapted to support a hat, a tool assembly including a tool for operating on said hat, means pivotally connecting said tool assembly to said base whereby said tool may traverse the crown portion of said hat, means for varying at will the radius of the path of traversal of said tool, means for mounting said tool assembly on said first-mentioned means for free swiveling movement in relation thereto, and means for varying at will the swivel axis of said tool assembly whereby variations in the traversal radius of the tool assembly may be compensated for by variations in the swivel axis thereof.

33. In a machine of the character described, in combination, a hat support adapted to support a hat, a tool for operating on the surface of the hat, means for effecting relative movement between the tool and the hat support in a path extending substantially from the tip of the hat toward the brim thereof, pneumatic means for holding the hat in operative position on the hat support as it is operated on by said tool, and hydraulic means for moving the hat support past the tool.

34. A tool assembly for a pouncing machine of the character described comprising, in combination, a housing, a crank shaft rotatably mounted in said housing and having at least two throws thereon, a tool rod connected to one of said throws, a tool connected to said tool rod, a balance rod connected to another of said throws and disposed in said housing, and means slidably related to said balance rod and adapted to rock about a fixed axis to coact with said balance rod in dampening vibration resulting from operation of said tool rod and tool.

35. A tool assembly for a pouncing machine of the character described comprising, in combination, a housing, a crank shaft rotatably mounted in said housing, a bearing member mounted on said casing and adapted to rock about a fixed axis, a tool rod connected to said crank shaft and slidably related to said bearing, a tool on said tool rod, balancing means connected to said crank shaft and disposed in said housing, and rocker means operatively associated with said balancing means to coact therewith in dampening vibration resulting from operation of said tool rod and tool.

36. In a pouncing machine, in combination, a base, a hat support associated with said base, the periphery of said hat support being adapted to support a hat, a pouncing tool for operating on a hat mounted on said hat support, and pneumatic means for effecting engagement between the hat and the hat support and for holding the hat on the hat support in proper operative position, said pneumatic means including a plurality of jets and a source of compressed air connected thereto and directed toward said support to force the hat thereagainst.

37. In a pouncing machine, in combination, a base, a hat support associated with said base and adapted to support a hat on its periphery, a pouncing tool for operating on said hat, an air jet adjacent said tool and adapted to direct a stream of air under pressure against said hat support to effect engagement between the hat and the hat support and to hold the hat in operative position on said hat support, and a source of compressed air for said jet.

38. In a machine of the character described, in combination, a hat support adapted to support a hat, a pouncing tool for operating on the surface of the hat, means for effecting relative movement between the tool and the hat support along a path extending substantially from the tip of the hat toward the brim thereof, means for rotating said hat support whereby upon engagement between the hat and the hat support, the hat is rotated, a member disposed about said hat support and about which the hat is adapted to be received in position for treatment by said tool, said member having an open portion and being stationary with respect to the rotation of the hat support, the open portion of said member being adjacent said hat support so that the hat may engage said support to be rotated thereby, means for forcing said hat against said hat support for rotation thereby, and means for moving the hat support axially past the tool.

39. In a machine of the character described, in combination, a hat support adapted to support a hat, a pouncing tool for operating on the surface of the hat, means for effecting relative movement between the tool and the hat support along a path extending substantially from the tip of the hat toward the brim thereof, means for rotating said hat support whereby upon engagement between the hat and the hat support the hat is rotated, a member disposed about said hat support and about which the hat is adapted to be received in position for treatment by said tool, said member having an open portion and being stationary with respect to the rotation of the hat support, the open portion of said member being adjacent said hat support so that the hat may engage said support to be rotated thereby, means for forcing said hat against said hat support for rotation thereby, a stationary cylinder, a piston in said cylinder connected to said mem-

ber and to said hat support, and means for reciprocating said piston in said cylinder to effect axial movement of said hat support past the tool.

40. In a machine of the character described, in combination, a base, a hat support rotatably mounted on said base and adapted to support a hat, a tool for operating on the surface of the hat, means for effecting relative movement between the tool and hat support along a path extending from the tip of the hat toward the brim portion thereof, pneumatic means for holding the hat in operative position on the hat support as it is operated on by said tool, a cylinder mounted on said base, a piston reciprocably disposed in said cylinder and connected to said hat support, and means for reciprocating said piston to move said hat support axially past the tool.

41. A hat support for a machine of the character described, comprising in combination, a hat support, means for rotating said support, a stationary member associated with said hat support and positioned with respect thereto so that a hat mounted on said stationary member may be engaged by said hat block, and pneumatic means adapted to be exerted against the outer surface of the hat for forcing a portion thereof against said hat support, whereby rotation of the hat support moves the hat relative to said stationary member.

42. In a machine of the character described, in combination, a base, a hat support on said base adapted to support a hat, means for rotating said hat support, a tool for operating on said hat, a support for said tool including mechanism for driving it through a closed substantially elliptical path, means for effecting relative movement between said supports, and means for freely piv-

otally supporting said tool support in operative relation to said hat support for unrestrained swiveling movement in relation thereto, the swivel axis of said tool being substantially parallel to the operating surface of said tool at least during operative engagement of the hat by the tool.

43. In a machine of the character described, in combination, a base, a hat support on said base adapted to support a hat, a tool assembly including a tool for operating on said hat, means for freely pivotally supporting said tool assembly in operative relation to said hat support for unrestrained swiveling movement in relation thereto, said tool assembly including a plurality of individual connected casings adapted to house a motor and tool driving mechanism driven by the motor, the center of mass of said tool assembly being coincident with the swivel axis thereof, and means connecting the tool to the tool driving mechanism.

44. In a pouncing machine, in combination, a base, a rotatable hat support associated with said base, the periphery of said hat support being adapted to support a hat, a tool support mounted on said base, means for effecting relative movement between said supports in a path extending from the tip of the hat toward the brim thereof, a pouncing tool movably mounted on said tool support for operating on a hat mounted on said hat support, and pneumatic means for effecting engagement between the hat and the hat support and for holding the hat on the hat support in proper operative condition during the operation of said pouncing tool thereon.

PAUL SCHULTZE.
